UNITED STATES PATENT OFFICE

114,992

DESIGN FOR AN OVERSHOE OR SIMILAR ARTICLE

Lucille B. Fitzgerald, Naugatuck, Conn., assignor to United States Rubber Company, New York, N. Y., a corporation of New Jersey

Application November 1, 1938, Serial No. 80,809

Term of patent 3½ years

To all whom it may concern:

Be it known that I, Lucille B. Fitzgerald, a citizen of the United States of America, residing at Bristol Terrace, Naugatuck, county of New Haven, State of Connecticut, have invented a new, original, and ornamental Design for an Overshoe or Similar Article, of which the following is a specification, reference being had to the accompanying drawing, forming part thereof, wherein:

The figure is a front perspective view of an overshoe, showing my new design.

I claim:

The ornamental design for an overshoe or similar article, as shown.

LUCILLE B. FITZGERALD.
